POCKET CONSTRUCTION

Louis Horwitz, El Paso, Tex., assignor to Hortex
Manufacturing Company, El Paso, Tex., a firm

Application March 9, 1945, Serial No. 581,781

5 Claims. (Cl. 2—253)

This invention relates to pocket constructions and more particularly to multi-compartment pockets, especially for garments.

An object of the invention is to provide a multi-compartment pocket so formed or constructed that pocket parts attached to a backing web or the like, for example part of a garment, can lie flat against the backing web so as to present a neat appearance, but in which the pocket or compartment-forming parts can be expanded to provide compartments of large capacity.

Another object is to provide a pocket construction of the character stated in which intermediate and outer webs are joined to the backing web by expansible V-shaped attaching edge sections.

A further object is to provide a pocket construction having mating V-shaped attaching edge sections joined at a pocket corner in an improved manner.

Other objects will become apparent from a reading of the following detail description, the appended claims, and the accompanying drawings, in which:

Figure 1 is a front view of a pocket construction embodying the invention;

Figure 2 is a section on the line 2—2 of Figure 1;

Figure 3 is a section on the line 3—3 of Figure 1;

Figure 4 is a fragmentary section of a bottom edge construction drawn on an enlarged scale;

Figure 5 is a fragmentary section of a side edge construction drawn on an enlarged scale;

Figure 6 is a fragmentary section on the line 6—6 of Figure 1;

Figure 7 is a plan view of a cut blank for forming an outer web member;

Figure 8 is a plan view of a cut blank for forming an intermediate web member;

Figure 9 is a plan view of a binding strip;

Figure 10 shows the blank of Figure 5 after its edge sections have been folded;

Figure 11 shows a modified assembly of intermediate and outer webs in which the entire outer web, including V-shaped attaching sections thereof, is disposed outside the intermediate section; and

Figure 12 is a view showing the intermediate and outer webs assembled as shown in Figure 11 with the binding strip added.

The illustrative embodiment shown in the drawings comprises a multi-compartment pocket including an outer web A, and an intermediate web B formed and attached in a novel manner

to a backing web C which may be, for example, a part of a garment. The pocket construction has a side edge 1 and a bottom edge 2 along which the outer web A and intermediate web 5 are joined to the backing web C. Along the opposite side edge 3 the intermediate web B is joined throughout its length to the backing web C and the outer web A is joined to the web C only adjacent the pocket bottom along the short line 3^a. A diagonal edge 4 of the outer web extends from the top of the line 3^a to a central part of the top edge 5 of the intermediate section. The diagonal edge 4 may be hemmed as shown at 6 in Figures 1 and 2 but is not joined to the intermediate section B, thus leaving the compartment between the webs A and B open. Similarly the top edge 5 of the intermediate web and the top edge of the web A extending to the left of the diagonal 4 may be bound as shown 15 at 7 in Figures 1 and 2 but are not joined to the backing web C.

By virtue of the novel construction presently to be described both of the webs A and B are connected to the web C along the side 1 and bottom 2 by expansible means, preferably pleats or sections with accordion-like folds enabling all three webs to lie close to each other when the compartments are empty but permitting the webs A and B to move away from the web C to expand or increase the capacity of the pocket compartments. As shown in Figures 1, 3 and 5 the edge portion of the outer web A along the pocket side 1 is formed as a V-shaped attaching section 8 including a part 8^a folded in under the web A, and a free edge part 8^b return-folded under the part 8^a. The free edge of the part 8^b is stitched at 9 to the backing web C, and preferably is turned under at 8^c. The contiguous edge portion of the intermediate web B overlaps and is joined to the attaching section 8, preferably being stitched as 20 at 10 to the attaching section part 8^a. By folding the edge of the web B at 11 and spacing the line of stitching 10 from the fold 11, expansion can take place between the webs A and B along the pocket side 1. A line of stitching 12 may be run adjacent the return fold between the parts 8^a and 8^b for assisting in maintaining the accordion-like nature of the attaching section 8.

As shown in Figures 1, 2 and 4 the edge portion of the outer web A along the pocket bottom 2 is formed as a V-shaped attaching section 13 including a part 13^a folded in under the web A and a free edge part 13^b return-folded under the part 13^a. The free edge of the part 13^b is stitched as at 14 to the backing web C, and preferably is

turned under at 3^c. The contiguous edge portion of the intermediate web B overlaps and is joined to the attaching section B, and may be stitched as at 15 to the fold between the web A and the attaching section part 13^a, the extreme edge 16 of the intermediate web B lying against the part 13^a as clearly shown in Figure 4. A line of stitching 13^x may be run adjacent the return fold between the parts 13^a and 13^b for assisting in maintaining the accordion-like nature of the attaching section 13.

Figures 7 to 12 inclusive show diagrammatically the basic or general forms of the blanks forming the webs A and B, and the binding 1, and indicate the sequence of steps in assembling the parts. Figure 7 shows the cut blank from which the outer web member A is formed. The blank includes a body portion, parts 8^a and 8^b for forming the V-shaped attaching section 8, and parts 13^a and 13^b for forming the V-shaped attaching section 13. A diagonal edge strip 17 is provided for hemming as shown in Figures 1 and 2. A part is cut out at the meeting ends of the edge sections 8 and 13 to provide resultant mating end edges 8^d and 13^d on the parts 8^a and 13^a respectively. The cut out also provides resultant mating end edges 8^e and 13^e on the parts 8^b and 13^b respectively.

After the sections 8 and 13 are folded the end edge 8^d is stitched to the end edge 13^d and the end edge 8^e is stitched to the end edge 13^e. This forms a very neat strong corner.

Preferably the lower corners of the intermediate web B are cut off as indicated in Figure 8 in order to avoid bunching of material at the corners when the webs A and B are assembled.

In order that the diagrammatic views, Figures 7 to 12 inclusive, may be as simple as possible so as to show the general organization at a glance, some of the parts shown in Figures 1 to 6 inclusive, for example the turned under hems 8^e and 13^e have been omitted from the diagrammatic views.

The pocket construction disclosed embodies the invention in the form now preferred, but it will be understood that changes may be made without departing from the invention as defined in the claims.

I claim:

1. In a multi-compartment pocket construction 50
a backing web; an intermediate web; an outer

web; pleated edge portions on said outer web forming V-shaped attaching sections; stitching joining free edges of said attaching section to said backing web; and other stitching joining the edges of said intermediate web to said attaching sections.

5 2. In a multi-compartment pocket construction a backing web; an intermediate web; an outer web; pleated edge portions on said outer web forming V-shaped attaching sections; and stitching joining free edges of said attaching sections to said backing web, edges of said intermediate web overlapping said V-shaped attaching sections respectively; and stitching joining said edges of said intermediate web to said V-shaped attaching sections respectively.

10 3. In a multi-compartment pocket construction a backing web; an intermediate web; an outer web; pleated edge portions on said outer web forming V-shaped attaching sections; and stitching joining free edges of said attaching sections to said backing web, edges of said intermediate web extending between said outer web and the portions of said V-shaped sections immediately adjacent said outer web; and stitching joining said edges of said intermediate web to attaching portions only on the sides of the V's which are adjacent said outer web.

15 4. In a multi-compartment pocket construction, 30 a backing web; an intermediate web; an outer web; and means including pleated V-shaped attaching sections joining contiguous edges of said intermediate web and said outer web to said backing web with freely expandable portions of the V-shaped sections being disposed between said backing web and the edges of both the intermediate web and the outer web.

20 5. A multi-compartment pocket construction as defined in claim 1 in which the outer web comprises a body portion, two intersecting V-shaped edge sections each of which includes a first part folded in under the body portion and a free edge part return-folded under said first part, there being a cut-out at the meeting ends of said edge sections providing resultant mating end edges on the respective first parts and resultant mating end edges on the respective free edge parts; and stitching joining said end edges to the respectively mating end edges.

LOUIS HORWITZ.
